UNITED STATES PATENT OFFICE.

JOSEPH STRONGE, OF ST. PAUL, MINNESOTA.

HAT.

1,212,842.

Specification of Letters Patent. Patented Jan. 16, 1917.

Application filed July 1, 1916. Serial No. 107,148.

To all whom it may concern:

Be it known that I, JOSEPH STRONGE, a citizen of the United States, residing at St. Paul, in the county of Ramsey and State of Minnesota, have invented new and useful Improvements in Hats, of which the following is a specification.

My invention relates to improvements in hats, with special reference to that class of 10 women's hats which is known as sport hats. These hats are usually made of felt with flexible brims, adapted to be given an unconventional outline and to be worn with the brim depressed or elevated or partly de- 15 pressed and partly elevated.

The particular object of my invention is to protect the brows and eyes of the wearer, while permitting a view of objects in advance, and at the same time to produce a 20 novel effect.

In the accompanying drawings, Figure 1 is an elevation of my improved hat, in place, with the brim depressed; Fig. 2 is an elevation of the hat, showing the front portion 25 of the brim turned up; and Fig. 3 is a detail section of Fig. 2, taken on the line 3—3.

The hat is designated in the drawings by the letter A, and the soft brim by the numeral 10. This brim is formed with an 30 opening 11, and a monocle 12, consisting of glass, celluloid, or other transparent material, covers the opening, said monocle being held in place by applying over the edges thereof a flexible annular frame 13, prefer- 35 ably of textile, knitted, crocheted, or embroidered material, with irregular external outlines. One side of this frame may be formed by the edge 14 of the opening 11 and the monocle may, if desired, be further 40 secured by stitches 15 through perforations 16 in the monocle. It will be obvious to those familiar with the millinery art that said monocle may be rendered more or less conspicuous by the character of the sur-

rounding applications. It will also be apparent that the front of the brim of the hat may be worn elevated, as shown in Fig. 2, when the monocle and its applied frame become effective decorations, or all of the front portion of said brim may be worn depressed, 50 when the upper part of the face of the wearer is effectively protected from glaring lights and the direct rays of the sun and the wearer is also shielded from the observation of the passer-by, without preventing the use of the eye over which the monocle is placed. It is also obvious that a lens fitted to the vision of the wearer, or colored glass, or other transparent substance may be used to further protect the eye and 55 at the same time assist in the decorative scheme of the hat.

Having described my invention, what I claim as new and desire to protect by Letters Patent, is:

1. A hat having a soft, perforated brim provided with a monocle of transparent material, and a frame of flexible material applied to the margin of the perforation and adapted to secure the monocle in place. 65
2. A hat having a soft brim adapted to be turned down over the brow of a wearer, a monocle over an opening in said brim and means for holding the monocle in place. 70
3. In a hat having a pendent brim, a monocle inserted in the front of said brim and held in place by a marginal application of ornamental fabric. 75
4. A hat having a soft brim adapted to be turned down over the brows of the 80 wearer, a monocle in a perforation in the front of said brim, and an irregular border of applied flexible material adapted to hold the monocle in place.

Whereof, I have hereunto subscribed my 85 name to this specification.

JOSEPH STRONGE.
